UNITED STATES PATENT OFFICE.

WALTER W. REED, OF ROCKLAND, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

ELECTRICALLY-HEATED APPARATUS FOR MOISTENING SHOES.

1,294,533.

Specification of Letters Patent. Patented Feb. 18, 1919.

Application filed August 19, 1915. Serial No. 46,286.

To all whom it may concern:

Be it known that I, WALTER W. REED, a citizen of the United States, residing at Rockland, in the county of Plymouth and State of Massachusetts, have invented certain Improvements in Electrically-Heated Apparatus for Moistening Shoes, of which the following description, in connection with the accompanying drawings, is a specification, like reference characters on the drawings indicating like parts in the several figures. This invention relates to apparatus used in the manufacture of boots and shoes, and particularly to apparatus for moistening shoes.

It has been found that much of the cracking and breaking of shoes which has been incident to the lasting operation can be avoided by preliminarily treating with hot vapor those portions of the shoes which are to be sharply bent during the lasting operation. Considerable difficulty, however, has been experienced in regulating and maintaining constant the temperature of the vapor which is applied to the shoes. Too high a temperature will cause the leather to shrivel up and "burn", while too low a temperature will not soften the leather sufficiently to effect successful lasting. I have found that a constant temperature and uniform amount of moisture is insured if the water from which the vapor is generated be maintained in the apparatus in a constant volume, the heat supplied uniformly to it, and the vapor applied directly to the work without opportunity for variation in pressure. It is accordingly an object of the present invention to provide a softening apparatus for boots and shoes which shall possess the advantages above discussed, and others which will be hereinafter set forth.

A feature of my invention comprises a compartment for the reception of portions of shoes, in communication with a chamber containing water maintained automatically at a constant level, and an electric-heating unit arranged to heat the water.

Another feature of my invention comprises a layer of absorbent material in contact with the upper surface of a body of water heated by an electric unit and automatic means for maintaining said upper surface at a constant level, whereby the vapor

generated from said water is tempered and diffused around the part of the shoe to be treated.

A further feature of my invention comprises a substantially open compartment for receiving portions of shoes for treatment and means for supplying steam to said compartment, whereby the surplus steam is allowed to diffuse into the air instead of remaining in contact with the shoes.

Other features of my invention, comprising certain arrangements and combinations of parts, will be described in the specification and pointed out in the claims.

The drawing shows a preferred embodiment of my invention in an apparatus for softening the toes of shoes.

The casing or tank 1 contains water, and a passage 2 leads from the bottom of the tank to a reservoir 3 which is kept full of water by the barometric feeding device 4. The water in the tank 1 is thus kept at constant level. Just below this level, in the tank 1, is a grating or support 5, above which is placed a pad of felt 6. This pad is recessed as at 7, to receive the toe of a pulled-over shoe 8.

The tank 1 has a recess 9 extending directly into the water chamber, in which is mounted an electric heating unit 10. The apparatus is substantially open at the top, above the pad 6, but inasmuch as these devices are generally used near an open window, it has been found advisable to provide a shield 11, to protect the pad 6 and the shoes from drafts.

The tank 1, having an unvarying quantity of water in it, is heated by the unit 10, which, under commercially obtainable constant voltage, generates heat at a uniform rate. The result is a substantially uniform generation of steam in the tank 1. The steam rises through the pad 6 and is cooled or "tempered" thereby. It diffuses through the pad which directs it evenly upon the portions of the shoe which it is desired to treat. The shoes are inserted as shown in the drawing, the recesses 7 being so short as to prevent wetting and consequent rotting of the tip seam. The uniform feed of tempered steam when once adjusted by a rheostat in connection with the unit 10, insures the desired softening without burning, of the materials at the toes of the shoes.

It is desirable to keep the insoles 13 from getting wet, since this softens and shrinks them and interferes with the proper performance of later operations involving them. I accomplish this result by leaving the toe receiving compartment substantially open, so that steam which rises from the felt 6 will be immediately taken up and dissipated by the air. The steam is permitted to rise directly and to pass off without passing over and in contact with the insole to any substantial extent since the open construction gives it an area through which to dissipate which is large in comparison with that of the toe of the shoe. There is accordingly, in my apparatus, no heavily steam laden atmosphere over the insoles, from which it is necessary to protect them. The shield 11 is merely for the purpose of deflecting strong currents of cold air, which would interfere with the softening operation.

Having described my invention, what I claim as new and desire to secure by United States Letters Patent is:—

25 1. A chamber for containing a quantity of water, an electric heating unit disposed in thermal communication with said chamber, means for automatically maintaining said quantity of water constant, and a compartment for the reception of shoes communicating with said chamber.

30 2. A water chamber, a barometric feeding means in communication with said water chamber, an electric heating unit appurtenant to said water chamber, and a compartment for treating shoes communicating with said chamber.

35 3. A water chamber, means for automati-

40 cally preventing the lowering of the level of the water in said chamber, a compartment for treating shoes above said chamber, a partition of absorbent material separating the chamber and the compartment, and in contact with the upper surface of the water in the chamber, and an electric heating unit in thermal communication with said water.

45 4. A chamber constructed and arranged for the generation of steam, a compartment for treating shoes above said chamber, and a partition of absorbent material separating the chamber and the compartment, said partition being recessed to receive the portions of shoes to be treated.

50 5. A substantially open compartment constructed and arranged to receive a portion of a shoe for treatment, and means for supplying steam to said compartment and applying it to the shoe, the compartment being freely open at the top to afford a dissipating area for the steam after it leaves the vicinity of the treated portion of the shoe which is large in comparison with the area of the toe of the shoe.

55 6. A support constructed and arranged to receive a shoe in an inverted position for treatment, means for applying vapor to the shoe, the treated portion of said shoe being closely inclosed by said means and the portion of the shoe not treated being unin- 60 closed, and a shield constructed and arranged to protect said means from drafts.

70 In testimony whereof I have signed my name to this specification.

WALTER W. REED.
